UNITED STATES PATENT OFFICE.

HENRY J. CHILTON, OF CHICAGO, ILLINOIS, ASSIGNOR, BY MESNE ASSIGNMENTS, TO
HERBERT D. LAFFERTY, OF OAKLAND, CALIFORNIA.

ENGINE-MANIFOLD.

1,330,580.

Specification of Letters Patent. Patented Feb. 10, 1920.

Application filed March 4, 1915. Serial No. 11,984.

To all whom it may concern:

Be it known that I, HENRY J. CHILTON, a citizen of the United States, residing in the city of Chicago, county of Cook, and State of Illinois, have invented certain new and useful Improvements in Engine-Manifolds, of which the following is a specification.

This invention relates to engine manifolds, and more particularly to a construction 10 adapted for internal combustion engines, though in its broader aspects the invention is not limited to such use.

The salient objects of the invention are to provide a construction whereby a single 15 manifold can be used for conducting both the inlet and exhaust gases; to so construct the engine and the manifold that the inlet and exhaust chambers are divided by a single partition wall, the surfaces of the dividing wall being free from any obstruction 20 that would deter the passage of the gases to or from the engine; to provide a construction whereby the inlet and exhaust passages and the dividing wall can be formed from a 25 single casting; to provide an improved construction of combined inlet and exhaust manifold whereby the incoming gases will be heated by the exhaust gases, but danger of overheating avoided; and in general to 30 provide an improved construction of combined inlet and exhaust manifold which can be cheaply manufactured and readily applied to various engines of standard construction.

35 In the drawings—

Figure 1 is a cross-section through one of the cylinders and the manifold;

Fig. 2 is a side elevation of the inner side of the manifold.

40 Referring to the particular embodiment of my invention shown in the drawings, 1 designates a cylinder of a multi-cylinder engine, and 2 the manifold through which the incoming charge is conducted to the various 45 cylinders and the exhaust gases led away therefrom. In gas engines such as are employed in automobiles, it is often desirable that the incoming gases be preheated, and for this purpose the heat of the exhaust gases is utilized. It is, however, inadvisable to heat the incoming gases to too high a temperature, and the present construction 50 contemplates an arrangement which will not overheat the incoming gases and in which the construction is greatly simplified.

As shown in the drawings in Fig. 1, the manifold 2 is divided by the partition 3 into two compartments 4 and 5, these compartments being arranged in different horizontal planes and forming inlet and exhaust 60 passages respectively. The particular construction shown is an engine of the vertical type, but it is obvious that, if my invention was applied to a horizontal engine, the passages 4 and 5 might be more conveniently 65 arranged in different vertical planes. The construction in either case is such that the passages 4 and 5 extend along the side of the cylinder, and each serve to conduct the gases to and from a plurality of ports. Thus 70 the exhaust passage 5 has a plurality of openings 6 each of which connects with an opening 7 in the outer end of the exhaust passage 9. In a similarly arranged manner the inlet passage 4 has a plurality of openings 10 each of which connects with an outer end 11 of the inlet passage 12 formed in the cylinder wall.

In both puppet and rotary valve constructions, it is often desirable to have the 80 inner ends of the exhaust and inlet ports opening in the same plane. Thus as shown in Fig. 1 the port 13 of the valve 14 can be used to control both the inlet and exhaust from the cylinder 15, the valve 14 being 85 driven in timed relation with the crank shaft by means of gearing 16. The particular construction of valve shown does not, however, form any part of the invention here presented, and any other type of valve could be 90 employed.

While the inner ends of the inlet and exhaust passages 12 and 9 open in the same plane, it is necessary that their outer ends terminate in different planes in order to 95 bring them in registration with the respective passages 4 and 5. This I have accomplished by curving or offsetting the passage 9 and 12 so that the openings 7 and 11 come respectively above and below the dividing 100 wall 3. This permits of maintaining the surfaces 17 and 18 of the dividing wall 3 uninterrupted throughout their lengths. The gases are, therefore, free to pass through the passages without being baffled against 105 each other, and danger of overheating the incoming gases is avoided. I have further guarded against such overheating by providing the outside of the manifold with a series of fins 19. While the latter are shown 110

as transversely arranged, it is obvious that longitudinal fins could be employed if desired.

The construction is such that the entire manifold including the inlet conduit 20 and the exhaust conduit 21 can be cast as a unitary structure. Moreover, there are no complicated parts, and by curving the inlet and exhaust conduits 9 and 11 in the manner shown in Fig. 1, it is possible to use the construction with an engine designed to have the inner end of its inlet and exhaust passages lying in the same horizontal plane. While I have shown and described but one form of obtaining the outer ends of the inlet and exhaust passages in different planes, it is obvious that various changes in construction and arrangement of parts can be made without departing from the scope of my invention, and I do not desire to limit the lat-

ter except as specified in the appended claim.

I claim as my invention:

In engine construction, the combination with a cylinder having inlet and exhaust passages leading through the cylinder walls, the inner ends of said passages lying in the same horizontal plane and the outer ends of said passages lying in different horizontal planes, of a manifold having ports connecting with the outer ends of said passages and a dividing wall positioned above the outer end of one of said passages and below the outer end of the other of said passages, for conducting the inlet and exhaust gases adjacent but out of contact with each other.

HENRY J. CHILTON.
